UNITED STATES PATENT OFFICE.

JOHN F. O'CONNOR, OF CHICAGO, ILLINOIS, ASSIGNOR TO W. H. MINER COMPANY, OF CHICAGO, ILLINOIS, A CORPORATION OF ILLINOIS.

DRAW-BAR-CENTERING DEVICE FOR RAILWAY-CARS.

No. 798,110.

Specification of Letters Patent.

Patented Aug. 29, 1905.

Application filed June 5, 1905. Serial No. 263,727.

To all whom it may concern:

Be it known that I, JOHN F. O'CONNOR, a citizen of the United States, residing in Chicago, in the county of Cook and State of Illinois, have invented a new and useful Improvement in Draw-Bar-Centering Devices for Railway-Cars, of which the following is a specification.

My invention relates to draw-bar-centering devices for railway-cars.

The object of my invention is to provide a draw-bar-centering device of a strong, simple, efficient, and durable construction and adapted to be adjusted to different positions to compensate for wear and to accommodate draw-bars of different widths or thicknesses.

My invention consists, in connection with the draw-bar, of a pair of draw-bar-centering arms or wings, secured to a pair of torsional rods, mounted upon arms or projections, with which the side plates or stop-castings of the draft-rigging are furnished, and which torsional rods are provided at their rear ends with adjusting-segments furnished with a plurality of holes for setting the draw-bar-centering arms or wings in different positions, as may be required.

In the accompanying drawings, forming a part of this specification, Figure 1 is a side elevation, partly in vertical section, of the device embodying my invention. Fig. 2 is a plan view, partly in horizontal section. Fig. 3 is a vertical section on line 3 3 of Fig. 1, and Fig. 4 is a vertical section on line 4 4 of Fig. 2.

In the drawings, A represents the center sills, A' the front or end sill, A² the buffer-block, A³ the carry-iron, and A⁴ the draft-timbers, of a car-frame to which my invention is applied.

B is the draw-head, B' the draw-bar, B² the draw-bar strap or yoke, C c C' c' tandem-arranged springs, D D the side plates or stop-castings, and E E' E² E³ the followers, of the draft-rigging.

All the above-named parts may be of any suitable or desired construction.

F F are a pair of draw-bar-centering arms or wings, each preferably of cast metal and

having a rounded head or face f, adapted to 50 bear against the vertical sides or faces of the draw-bar. Each of these centering arms or wings F is secured to a torsional rod G and is furnished with a pivot portion f', fitting in a rounded socket or bearing d' in a downwardly- 55 extending bracket, arm, or extension D', either integral with or separately attached to the side plate or stop-casting D. The bracket or extension D' of the side plate or stop-casting is also furnished with a lip or shoulder d'', which 60 serves as a stop to limit the downward movement of the draw-bar-centering arm or wing F. Each of the torsional rods G is provided at its rear arm with an adjusting-segment G', furnished with a series of holes g, so that the 65 torsional rod may be regulated or adjusted as required by setting the segment G' in different positions by means of the pin g', which is furnished with a key g''. Each of the side plates or stop-castings D is provided with a 70 bracket or arm D'', either integral with or separately attached to the casting at its rear end, through which the torsional rod G extends. The torsion-rod G is furnished at each end with keys g'' g''' to keep the same in place. 75 The side plates or stop-castings D are furnished with recesses or cavities d''' to receive the centering arm or wing F.

I claim—

1. In a draw-bar-centering device, the combination with a draw-bar, and side plates or stop-castings furnished with downwardly-projecting arms or brackets, of draw-bar-centering arms or wings pivotally mounted in said arms or brackets, and torsion-rods to 85 which said centering arms or wings are secured, substantially as specified.

2. In a draw-bar-centering device, the combination with a draw-bar, and side plates or stop-castings furnished with downwardly-projecting arms or brackets, of draw-bar-centering arms or wings pivotally mounted in said arms or brackets, and torsion-rods to 90 which said centering arms or wings are secured, and adjusting-segments secured to the other ends of said torsion-rods, substantially as specified.

3. The combination with the draw-bar, of

torsion-rods extending parallel to the draw-bar, and centering-arms secured to said torsion-rods, substantially as specified.

4. The combination with the draw-bar, of
5 torsion-rods extending parallel to the draw-bar, and centering-arms secured to said torsion-rods, and segments secured to the op-

posite ends of said torsion-rods from the centering-arms for adjusting the same, substantially as specified.

JOHN F. O'CONNOR.
